UNITED STATES PATENT OFFICE.

THOMAS H. McALLISTER, OF NEW YORK, N. Y.

LAMP FOR MAGIC LANTERNS.

SPECIFICATION forming part of Letters Patent No. 339,451, dated April 6, 1886.

Application filed January 28, 1886. Serial No. 190,134. (No model.)

To all whom it may concern:

Be it known that I, THOMAS H. McALLISTER, of the city, county, and State of New York, have invented a new and useful Improvement in Lamps, of which the following 5 is a specification, reference being had to the annexed drawings, forming a part thereof, in which—

Figure 1 is a front elevation. Fig. 2 is a 10 vertical transverse section taken on line xx in Fig. 3. Fig. 3 is a sectional plan view taken on line yy in Fig. 2. Fig. 4 is a diagram showing the relation of the lamp to the lantern in connection with which it is to be 15 used.

Similar letters of reference indicate corresponding parts in the different figures of the drawings.

My invention relates to the class of lamps 20 employed in connection with magic lanterns and other optical instruments, and is designed to secure a uniformly-illuminated field. It is common to provide lamps for this purpose with double wicks; but when such wicks are 25 arranged parallel with each other and with the axis of the lenses of the instrument the break in the flame which unavoidably occurs between the two wick-tubes causes a dark spot upon the center of the screen, which is 30 objectionable.

The object of my invention is to obviate this difficulty, and I accomplish this end by arranging the wick-tubes of the lamp diagonally with reference to the axis of the lenses, as 35 shown in Fig. 4, so that the two flames from which the light emanates overlap each other, thereby avoiding the dark space.

In addition to the features above described, my invention consists in a metallic chimney 40 having an enlarged portion provided with a reflector and with a removable glass window, as hereinafter more fully described.

To the top of the reservoir A of the lamp are secured two wick-tubes, B B', which are arranged diagonally across the top of the lamp reservoir, and are provided with the usual spindles, a , and spurs attached thereto, for raising and lowering the wicks contained by the tubes.

To standards b , secured to the top of the reservoir A, is secured a chimney-holder, C, which surrounds the wick-tubes B near their

upper ends, and contains a perforated diaphragm, c , which closes the opening in the chimney-support, with the exception of slits 55 for the wick-tubes B. A stop, d , is secured in the chimney-support at right angles to the center line of the reservoir of the lamp, and the cone D, which is common to both wick-tubes, has a segmental portion removed from one 60 edge thereof, to admit of placing it in the chimney-holder C within the stop d , and to cause it to register with the wick-tubes. The lower portion, E, of the chimney is of cylindrical form, and has an opening, e , in one side thereof, with a bar, f , extending across the open side at the bottom of the chimney and received within the stop d . The edges of the section E of the chimney are flattened at opposite sides of the opening e , to receive the glass plate g , 70 which closes the opening e , and is held in place by flanges h , riveted to the top of the chimney at opposite sides of the opening e . The glass plate g is prevented from escaping from behind the flanges h by bending the lower ends 75 of the flanges, as shown in Fig. 2.

To the inner surface of the body E of the chimney opposite the opening e is fitted a curved mirror, i , which reflects the light from the back of the flame of the lamp through the 80 opening e .

To the top of the body E is fitted a cap, F, corresponding to the general form of the body, and having a flattened side, j , which extends across the open side of the body E, and causes 85 the cap to register with the other parts of the lamp. In the middle of the cap is formed an elliptical opening, k , which is surrounded by an upwardly-projecting collar, l , for receiving the upper portion, G, of the chimney. 90

The lamp is provided with the usual screw-capped opening, m , for the purpose of filling.

The lamp is placed in a suitable position in the lantern, with the opening e facing the condensers. 95

Having thus described my invention, what I claim as new, and desire to secure by Letters Patent, is—

1. In a lamp for lanterns and other optical instruments, two or more wick-tubes arranged 100 diagonally with reference to the axis of the lenses of the instrument, substantially as herein shown and described.

2. In a lamp for optical instruments, the

combination, with the diagonally-arranged wick-tubes, of the chimney-support C, provided with the stop d, the cone D, having a portion of one edge cut away to cause it to register with the wick-tubes, a metallic chimney-body, E, open in one edge thereof and provided with a glass plate, g, the cap F, having the elliptical opening k, and the chimney-top G, fitted to the elliptical collar, substantially as herein shown and described.

3. The combination, in a lamp for optical instruments, of the reservoir A, provided with the diagonally-arranged wick-tubes B, the chimney-support C, the chimney-body E, open in one side, the glass plate g, the cone D, the

centrally-apertured cap F, and the chimney-top G, substantially as herein shown and described.

4. As an improved article of manufacture, a lamp formed of the reservoir A, diagonally-arranged wick-tubes B, wick-operating spin-dles a, the chimney-support C, provided with the stop d, the chimney-body E, open in one side, the glass plate g, fitted to the opening, the curved reflector i, the cap F, and the chimney-top G, substantially as herein shown and described.

THOS. H. McALLISTER.
